UNITED STATES PATENT OFFICE.

OLE SEVERSON, OF RANDALL, KANSAS.

FARM-GATE.

1,104,010.

Specification of Letters Patent. Patented July 21, 1914.

Application filed January 26, 1914. Serial No. 814,474.

To all whom it may concern:

Be it known that I, OLE SEVERSON, citizen of the United States of America, residing at Randall, in the county of Jewell and 5 State of Kansas, have invented certain new and useful Improvements in Farm-Gates, of which the following is a specification.

This invention relates to gates, more particularly to operating devices therefor, the 10 object of the invention being to provide an improved and simplified operating mechanism by means of which the driver of a vehicle approaching the gate can open the gate from a distance, the gate being locked 15 in its open position during the time the driver is passing therethrough, together with means for releasing the gate and permitting it to close after the vehicle has passed through the gate.

20 Further objects and advantages of the invention will be set forth in the detailed description, which now follows:

In the accompanying drawing, Figure 1 is a side view of a gate constructed in accordance with the invention. Fig. 2 is a horizontal section through a casing which contains the latch for holding the gate in its open position. Fig. 3 is a detailed side view of a slotted rib employed in conjunction with said catch mechanism, and Fig. 30 4 is a detailed view of one of said catches.

Like numerals designate corresponding parts in all of the figures of the drawing.

Referring to the drawing, numeral 5 designates a gate which may be of any desired shape or construction. A hanger comprising vertical members 6 and braces 7 supports said gate, said hangers being provided with a plurality of vertical spaced openings 40 by means of which the gate may be vertically adjusted as for instance, when there has been a heavy fall of snow. The vertical members 6 carry rollers or wheels 8 which travel upon a wire 9. This wire 45 may be slightly inclined, as shown in Fig.

1, if desired and the gate may close by gravity, or a cable 10 may be attached to the hanger and passed over a pulley 11, carried by a post 12, said cable being then attached to a ring 13 which slides upon a guy extension 14, of wire 9, and a weight 15 is attached to the ring. The post 12 carries in front, the guide member indicated at 16, for centering the gate with relation to the post. 50 Guide posts 17, only one of which is shown, are disposed upon opposite sides of the gate

near the rear end thereof, when the gate is in its closed position. A single short cable 18, extends from the rear end of the gate to a ball or button or like enlarged device 19, 60 and from that point the two cables 20 and 21 extend rearwardly, and into the catch mechanism casing indicated at 22. This casing is of box like formation and comprises the side walls 23, front wall 24, and the bottom 25. The bottom 25 is cut out at its rear end to conform to the shape of a post 26. Bolts 27 pass from the rear ends of the side walls 23 and through the post, and secure the casing in place upon said post. Guide pulleys or spools 24' are journaled at 25', within the casing, over which the cables 20 and 21 pass. A rib 28 is centrally disposed within the casing and is provided with a slot 28'. Latches comprising upturned arms 29, and downturned arms 30, which travel in and have their movement limited by slots 30' have their portions 31 pivoted in ears 32 of the casing. 70

The operation of the device is as follows: The driver of a vehicle approaching the gate from the near side in Fig. 1, pulls upon cable 21 which may be extended any desired distance from the gate, thereby drawing the gate to the right against the action of gravity, or against the action of weight 15, or both, until the ball 19 passes into the casing 22, and since the pulley upon cable 21 tends to draw the ball over toward the 80 right hand side of the casing, this ball engages in the crotch formed by the members 29 and 30, and the latch as a whole is swung rearwardly against the tension of a spring 33 which is attached to said latch and to a post 34. This permits the ball to pass the latch and then when the cable is slackened the ball engages behind the latch as shown in Fig. 2. The gate is then held in its open position while the vehicle passes there-through. 90

After the vehicle has passed through the gate and it is desired to close the same, the driver pulls upon cable 20. It will be noted that this cable passes through slot 28' and while this slot permits the passage of the cable therethrough, it is of such width that it prevents the passage of the ball. The reason for providing this rib is to prevent the ball from being jerked directly across the casing and engaging behind the opposite latch. This pull on cable 20 draws the 100 110

ball over against the rib 28 and then when the cable 20 is slackened the gate may close.

It is apparent that the gate may be opened from the far side in Fig. 1 by first pulling upon cable 20, which will draw the ball over to the left hand side of the casing to engage behind the latch on that side.

While the elements shown and described are well adapted to serve the purposes for which they are intended, it is to be understood that the invention is not limited to the precise construction set forth, but includes within its purview such changes as may be made within the scope of the appended claims.

Having described my invention, what I claim is:

1. The combination with a sliding gate, of means normally tending to close said gate, a latch casing, a pair of cables extending in opposite direction from said latch casing, an enlarged member to which both of said cables are attached, a connection from said enlarged member to the gate, and a pair of swingingly mounted latch elements mounted in said casing and behind which said enlarged member engages to hold the gate in its open position.

2. The combination with a sliding gate, of means normally tending to close said gate, a latch casing, a pair of cables extending in opposite directions from said latch casing, an enlarged member to which both of said cables are attached, a connection from said enlarged member to the gate, a pair of swingingly mounted latch elements mounted in said casing and behind which said enlarged member engages to hold the gate in its open position, and guide members arranged within said casing and over which said cables pass, said guide members being arranged in such manner that a pull upon one of said cables engages said enlarged member with one of said latches and a pull upon the other of said cables releases said enlarged member from said latch.

3. The combination with a sliding gate, of means normally tending to close said gate, a latch casing, a pair of cables extending in opposite direction from said latch casing, an enlarged member to which both of said cables are attached, a connection from said enlarged member to the gate, a pair of swingingly mounted latch elements mounted in said casing and behind which said enlarged member engages to hold the gate in its open position, guide members arranged within said casing and over which said cables pass, said guide members being arranged in such manner that a pull upon one of said cables engages said enlarged member with one of said latches and a pull upon the other of said cables releases said enlarged member from said latch, and vice versa.

4. The combination with a sliding gate, of means normally tending to close said gate, a latch casing, a pair of cables extending in opposite direction from said latch casing, an enlarged member to which both of said cables are attached, a connection from said enlarged member to the gate, a pair of swingingly mounted latch elements mounted in said casing and behind which said enlarged member engages to hold the gate in its open position, guide members arranged within said casing and over which said cables pass, said guide members being arranged in such manner that a pull upon one of said cables engages said enlarged member with one of said latches and a pull upon the other of said cables releases said enlarged member from said latch, and a guide member through which the last named cable passes, said guide member being arranged to prevent the movement of said enlarged member across said casing.

5. The combination with a sliding gate, of means normally tending to close said gate, a latch casing, a pair of cables extending in opposite direction from said latch casing, an enlarged member to which both of said cables are attached, a connection from said enlarged member to the gate, a pair of swingingly mounted latch elements mounted in said casing and behind which said enlarged member engages to hold the gate in its open position, guide members arranged within said casing and over which said cables pass, said guide members being arranged in such manner that a pull upon one of said cables engages said enlarged member with one of said latches and a pull upon the other of said cables releases said enlarged member from said latch, and a vertically arranged rib disposed longitudinally within said casing and having a longitudinally extending slot formed therein which opens at the front end of said rib, said slot being of such width as to permit the passage of one of said cables but prevent the passage of said enlarged member.

6. The combination with a sliding gate, of means normally tending to close said gate, a latch casing, a pair of cables extending in opposite direction from said latch casing, an enlarged member to which both of said cables are attached, a connection from said enlarged member to the gate, a pair of swingingly mounted latch elements mounted in said casing and behind which said enlarged member engages to hold the gate in its open position, guide members arranged within said casing and over which said cables pass, said guide members being arranged in such manner that a pull upon one of said cables engages said enlarged member with one of said latches and a pull upon the other of said cables releases said enlarged member from said latch, and

means normally tending to swing said latch members to a position cross-wise of said casing.

7. The combination with a sliding gate, 5 of means normally tending to close said gate, a latch casing, a pair of cables extending in opposite directions from said latch casing, an enlarged member to which both of said cables are attached, a connection from said 10 enlarged member to the gate, a pair of swingingly mounted latch elements mounted in said casing and behind which said enlarged member engages to hold the gate in its open position, guide members arranged 15 within said casing and over which said cables pass, said guide members being arranged in such manner that a pull upon one of said cables engages said enlarged member with one of said latches and a pull upon 20 the other of said cables releases said enlarged member from said latch, and means limiting the throw of said latch members.

8. In a device of the character described, the combination with a supporting member

of a pair of guide pulleys journaled there- 25 in, a rib extending longitudinally of said sup- port the major portion of which is disposed in advance of said pulleys, said rib having a longitudinally extending slot formed there- 30 in, which opens at the front end of said rib, a pair of cables passing over said pulleys, 35 an enlarged member to which said cables are connected, a gate, a connection between said enlarged member and said gate, a pair of opposed swingingly mounted latch mem- 40 bers each of which comprises a pair of divergent arms, said support having arcuate slots formed therein, in which the lowermost of said arms travel, and springs normally tending to move said latch members to bring 45 said lowermost arms against the forward ends of said slots.

In testimony whereof I affix my signature in presence of two witnesses.

OLE SEVERSON.
